UNITED STATES PATENT OFFICE.

SAM HOVESEPEAN, OF BUFFALO, NEW YORK.

DESIGN FOR A BILL FOLDER.

Application filed November 28, 1921. Serial No. 518,459. Term of patent 3½ years.

To all whom it may concern:

Be it known that I, SAM HOVESEPEAN, a citizen of the United States, residing at Buffalo, in the county of Erie and State of New York, have invented a new, original, and ornamental Design for a Bill Folder, of which the following is a specification, reference being had to the accompanying drawing, forming part thereof.

I claim:

The ornamental design for a bill folder, as shown.

SAM HOVESEPEAN.
